GAME APPARATUS

John B. Firestone, Brooklyn, N. Y., assignor to
John F. Meyer, Chicago, Ill.

Application December 24, 1934, Serial No. 758,958

18 Claims. (Cl. 273—121)

This invention relates to a game apparatus.

It is an object of this invention to provide an improved game apparatus which is relatively simple and inexpensive in construction and efficient in use.

A further object of the present invention is to provide the game apparatus hereinafter described and claimed.

An additional object of the present invention is to provide in a game apparatus, the combination of: a cabinet having a sight opening provided therein and including an inclined playing board having a ball exit opening formed therein; means for propelling balls onto the upper portion of said inclined playing board so that they may gravitate thereover and enter into said exit opening; an inclined runway arranged below said inclined playing board in communication with said ball exit opening for conducting spent balls back to a point adjacent to, but below, said propelling means; said runway having a ball exit opening or pocket formed therein in the lower portion thereof; a score-indicating device in said cabinet including a pivotal indicator having spaced score-indicating indicia thereon and said indicator having a relatively blank space thereon between said indicia; means normally urging said indicator into a position to dispose the said relatively blank space thereon in registration with said sight opening; and said score-indicating device including a member arranged in said pocket and actuated by balls entering said pocket to pivot said indicator at different times into a position to dispose said indicia selectively in registration with said sight opening against the action of said urging means.

Other objects will appear hereinafter.

The invention consists in the novel combination and arrangement of parts to be hereinafter described and claimed.

The invention will best be understood by reference to the accompanying drawings, showing the preferred form of construction and in which:

Fig. 1 is a top plan view of an amusement game cabinet having a preferred form of the present invention embodied therein;

Fig. 2 is a vertical longitudinal sectional view on line 2—2 in Fig. 1;

Fig. 3 is a plan view of a preferred arrangement of runways embodied in the new game apparatus;

Fig. 4 is a transverse vertical sectional view on line 4—4 in Fig. 3;

Fig. 5 is an enlarged perspective detail view, partly in section, of a score-indicating or registering device embodied in the new game apparatus; and

Fig. 6 is a sectional detail view of the score-indicating device shown in Fig. 5.

The present invention is designed particularly

for use with, and is shown in the drawings in conjunction with, a game apparatus of the so-called "pin" game, or "pin and marble" game, type, and such a game apparatus is generally indicated at 10 in the drawings. The apparatus 10 comprises a cabinet 11 in which is arranged an inclined playing board 12 and this playing board 12 is provided with ball exit openings 13. Extending around the marginal edge of the playing surface or inclined playing board 12 is a ramp 14 and arranged at the lower end of the ramp 14 is a propelling device or plunger 15 by means of which balls may be propelled, one at a time, around the ramp 14 onto the playing surface 12 so that they may enter into and pass through the ball exit openings 13.

Pivottally mounted on the inclined playing board 12, in conjunction with each of the ball exit openings 13, is a trap or door 16; these traps or doors 16 being hinged to the inclined playing board 12, as at 17, and each of the same having an arm 18 depending below the inclined playing board 12.

When a spent ball falls through one of the ball exit openings 13, it falls into a corresponding one of a series or group of runways 20 (Fig. 3). These runways 20 are arranged upon an inclined floor 19 which, in turn, is arranged below the playing board 12, and each of these runways 20 has communication with a preselected group of the ball exit openings 13. When a spent ball enters one of the runways 20 it gravitates toward the lower end of the same and actuates one of the score-indicating units 45 (Figs. 4, 5 and 6) in a manner set forth hereinafter.

Each of the inclined runways 20 includes an enlarged lower end portion 21 and arranged in each of these enlarged end portions 21 (Fig. 5) is a group of ball-deflecting pins 22 which serve to divide the lower end portion 21 of each runway 20 into two diverging routes or branches 23 and 24.

Formed in the inclined lower floor 19, adjacent the lower end portion 21 of each runway 20, is a ball exit opening or pocket 25 and slidably mounted below the inclined floor 19, so as to hold balls temporarily in the pockets or exit openings 25, is a slide plate or ball-releasing member 26.

Slidably mounted in the lower end wall 27 of the cabinet 11 is a coin slide 28 which has a depending arm 29; and when the coin slide 28 is moved inwardly (left to right, Fig. 2) the depending arm 29 carried thereby engages the slide plate 26 and thereby moves the latter (left to right, Fig. 2) so as to dispose the openings 30 formed therein in registration with the openings or pockets 25 formed in the floor 19, whereupon the spent balls held in the pockets 25 by the slide plate 26 drop through the exit openings 30 in the latter onto an inclined runway 31 by which they

are returned into a transverse runway 32; the balls being fed by the transverse runway 32 back to a point adjacent to, but below, the propelling means 15, for replay.

5 Slidably arranged below the inclined playing board 12 is a slide plate 33. This slide plate 33 has openings 34 formed therein into which the tongues 18 of the traps 16 project, and those portions of the slide plate 33 which define the marginal edges of these openings 34 are engageable with the tongues or arms 18 of the traps 16 so as to reset or move the latter into open position.

10 Carried by and depending from the slide plate 33 is an arm 35 (Fig. 2) and this arm 35 is engageable with the inner end of the coin slide 28, (right hand end, Figs. 2 and 3).

15 Mounted on the lower inclined floor 19 in the enlarged lower end portion 21 of each runway 20 is a supporting bracket 36 which has a pair of spaced upright extensions 37. The bracket 36 also has an arm 38 which projects above the extensions 37 thereof. Extending between, and having its ends journalled in, the extensions 37 of each of the brackets 36 is horizontal shaft 39 and each of these shafts 39 carries a score indicating or registering device which is generally indicated at 40 (Figs. 5 and 6). Each of the score-indicating or registering devices 40 includes a base plate 41. Each of these base plates 41 is associated with one of the pockets or ball-exit openings 25 and each base plate 41 includes two downwardly and oppositely angled or curved end portions 42 and 43 (Figs. 4 and 5) which normally project into the corresponding pocket 25.

20 35 Each of the score-indicating or registering devices 40 also includes an upright arm 44 and carried by each arm 44 at the upper end thereof is a score-indicating member in the form of a segmental dial or plate 45. Each of these indicators 40 40 has a relatively blank portion 46 and each indicator 45 has oppositely angled score indicia-bearing end portions 47 and 48 which are arranged on opposite sides of the relatively blank central portion 46. The relatively blank central portions 46 of the indicators 45, as well as the indicia-bearing angled end portions 47 and 48 thereof are visible, at different times, through sight openings 49; these openings 49 being formed in housings 50 which are arranged in the cabinet 11 above the inclined playing board 12.

25 45 The score indicators 45 and their supporting arms 44, are normally held by resetting springs 51, in a position wherein the relatively blank central portions 46 of the indicators 45 are visible through the sight openings 49; these re-setting springs 51 being attached at their upper ends to the adjacent and corresponding bracket arms 38 and being attached at their lower ends to the upward extensions 52 of the indicators 45.

50 60 The score indicators 45 and their supporting arms 44, are normally held by resetting springs 51, in a position wherein the relatively blank central portions 46 of the indicators 45 are visible through the sight openings 49; these re-setting springs 51 being attached at their upper ends to the adjacent and corresponding bracket arms 38 and being attached at their lower ends to the upward extensions 52 of the indicators 45.

Operation

65 70 Balls are played, one at a time, around the ramp 14, onto the inclined playing surface 12, by means of the propelling device 15, so that they may enter into the ball exit or scoring openings 13, whereupon, falling through the exit openings 13, they engage the tongues 18 thereof and close the traps 16 so as to prevent additional balls from being played through the corresponding exit openings 13.

75 The played balls which fall through the exit openings 13 pass into the corresponding inclined runways 20 and traveling by gravity down the latter, are deflected by the pins 22 (Fig. 5) into

either one of the two branches 23 or 24 of the corresponding runway 20.

80 Thus, assuming that a ball is deflected by the pins 22 into the branch 23 of one of the runways 20, it will then pass into the corresponding exit opening or pocket 25 and fall upon the angled end portion 43 or base of the indicating device 40, thereby pivoting the indicating device 40 clockwise, Fig. 5, against the action of its resetting spring 51; thus pivoting the indicia-bearing angled end portion or face 48 of the indicator 45 (clockwise, Fig. 5) into registration with the corresponding sight opening 49 so as to expose to view the score-indicating indicium 53 thereon.

85 Conversely, if the played ball is deflected by the pins 22 into the branch 24 of the runway 20 it will fall upon the angled end portion 42 of the base plate 41 of the corresponding indicating device 40, and in so doing, will pivot the indicating device 40 (counterclockwise, Fig. 5), against the action of its resetting spring 51, so as to expose to view through the corresponding sight opening 49 the flag or indicium-bearing end portion 47 of the corresponding indicator 40 and the score-indicating indicium 54 thereon.

90 25 The indicia 53 and 54 on the flags or indicators 53 and 54, respectively, are in the preferred and particular form of the invention shown in the drawings, the indicia used in playing the so-called game of "Tic-Tac-Toe", and it is to be noted that a bank of sight openings 49 are provided in the cabinet 11 above the playing surface 12 in acrostic rows (Fig. 1) and corresponding number of the indicators 46-47-48, etc., are arranged therebelow, so that the player may attempt to play balls into the ball exit or scoring openings 13 in such a manner as to actuate the flags or indicators 40-45-46 etc., according to a selected pattern of acrostic rows or sight openings 49.

95 40 The indicator flags 47 or 48 are held in registration with the sight openings 49, by entrapment of the spent balls 55 in the pockets 25 between the angled end portions 42 and 43 respectively, of the base plates 41 of the indicators 40 until such time as the coin slide 28 is moved inwardly (left to right, Fig. 2), whereupon the depending arm 29 of the coin slide 28 engages the lower edge portion of the slide plate 26 and thus moves the openings 30 therein into registration with the exit openings or pocket 25 which are formed in the floor 19. The trapped balls 55 then fall into the inclined runway 31 by which they are returned to the transverse runway 32 to be fed by the latter to a point adjacent to but below the propelling device 15 for replay.

100 45 As the coin slide 28 is moved inwardly (left to right, Fig. 2), the inner end of the coin slide (right-hand end, Figs. 2 and 3) engages the depending arm 35 of the slide plate 33, thereby shifting the portions of the slide plate 33 which define the marginal edges of the openings 34 formed therein in engage the tongues 18 of the traps 16 and thereby pivot the latter into open position (counterclockwise, Fig. 2).

105 50 It is to be noted that the new game apparatus embodies, in a large measure, the element of suspense to the player, since the player is unable to tell, even after ascertaining the particular exit opening 13 through which a played ball has fallen, which of the two score-indicators or flags 47-48 associated therewith will be actuated thereby and brought into registration with the corresponding sight opening 49, since the played ball, travelling

down the runway 20, may be deflected by the pins 22 arranged therein into either branch 23-24 of the runway 20 and hence may actuate either of the flags or indicators 41-48 of the corresponding score-indicating device 40.

It is to be understood that the particular indicia 53-54 shown on the flags or indicators 48-47 respectively are merely illustrative of indicia which may be used for playing the so-called game of "Tic-Tac-Toe" and that the indicia shown may be replaced by any other desired score-indicating indicia.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. In a game apparatus, the combination of: a cabinet having a sight opening formed therein and including an inclined playing board having a ball exit opening formed therein; means for propelling balls onto the upper portion of said inclined playing board so that they may gravitate thereover and enter into said exit opening; an inclined runway arranged below said inclined playing board in communication with said ball exit opening for conducting spent balls back to a point adjacent to, but below, said propelling means; said runway having a ball exit opening or pocket formed therein in the lower portion thereof; a score-indicating device in said cabinet including a movably mounted indicator having spaced score-indicating indicia thereon and said indicator having a relatively blank space thereon and means normally urging said indicator into a position to dispose the said relatively blank space thereon in registration with said sight opening; said score-indicating device including a member actuated by balls entering the said pocket to move said indicator, against the action of said urging means, and at different times, into a position to dispose said indicia selectively in registration with said sight opening.

2. In a game apparatus, the combination of: a cabinet having a sight opening formed therein and including an inclined playing board having a ball exit opening formed therein; means for propelling balls onto the upper portion of said inclined playing board so that they may gravitate thereover and enter into said exit opening; an inclined runway arranged below said inclined playing board in communication with said ball exit opening for conducting spent balls back to a point adjacent to, but below, said propelling means; said runway having a ball exit opening or pocket formed therein in the lower portion thereof; a score-indicating device in said cabinet including a movably mounted indicator having a relatively blank space thereon between said indicia; and means normally urging said indicator into a position to dispose the said relatively blank space thereon in registration with said sight opening; said score-indicating device including a member having portions projecting into said pocket and actuated by balls entering the said pocket to move said indicator against the action of said urging means, and at different times, into a position to

dispose said indicia selectively in registration with said sight opening.

3. In a game apparatus, the combination of: a cabinet having a sight opening formed therein and including an inclined playing board having a ball exit opening provided therein; means for propelling balls one at a time onto the upper portion of said inclined playing board so that they may gravitate thereover and enter into said exit opening; an inclined runway arranged below said inclined playing board in communication with said ball exit opening for conducting spent ball back to a point adjacent to but below said propelling means; said runway having a ball exit opening or pocket provided therein in the lower portion thereof; means dividing said runway into branches having communication with said pocket at opposite ends of the latter; a score-indicating device including an indicator having spaced indicia thereon selectively movable into registration with said sight opening; said indicating device including a member having oppositely extending and downwardly angled end portions projecting into said pocket balls travelling from the said branches of said runway into said pocket to move said indicator into position to dispose said indicia at different times in registration with said sight openings; means normally urging said indicator into a position to dispose said indicia out of registration with said sight opening; and a ball-releasing member arranged in said cabinet below said runway and pocket and coacting at different times with the said downwardly angled end portions of the said first-named member to hold balls in said pocket and to hold said indicator in position to dispose said indicia at different times in registration with said sight opening.

4. In a game apparatus, the combination of: a cabinet having a sight opening formed therein and including an inclined playing board having a ball exit opening provided therein; means for propelling balls one at a time onto the upper portion of said inclined playing board so that they may gravitate thereover and enter into said exit opening; an inclined runway arranged below said inclined playing board in communication with said ball exit opening for conducting spent balls back to a point adjacent to, but below, said propelling means; said runway having a ball exit opening or pocket provided therein; in the lower end portion thereof; and said runway having branches communicating with said pocket; a score indicating device in said cabinet including an indicator member having spaced indicia thereon movable at different times into registration with said sight opening; and means actuated by balls entering said pocket from the said branches of said runway to move said indicator at different times in opposite directions and thereby move indicia selectively into registration with said sight opening.

5. In a game apparatus, the combination of: a cabinet having a sight opening formed therein and including an inclined playing board having a ball exit opening provided therein; means for propelling balls one at a time onto the upper portion of said inclined playing board so that they may gravitate thereover and enter into said exit opening; an inclined runway arranged below said inclined playing board in communication with said ball exit opening for conducting spent balls back to a point adjacent to but below said propelling means; said runway having a ball exit opening or pocket provided therein in the

- lower portion thereof and having branches communicating with said pocket; a score indicating device in said cabinet including an indicator member having spaced indicia thereon 5 selectively movable into registration with said sight opening and having a relatively blank space between said indicia; means normally urging said indicator into a position to dispose said relatively blank space in registration with said sight 10 opening; and means actuated by balls entering said pocket from the said branches of said runway to move said indicator at different times in opposite directions, against the action of said urging means, and thereby move said indicia selectively into registration with said sight opening. 15
6. In a game apparatus, the combination of: a cabinet having a sight opening formed therein and including an inclined playing board having a ball exit opening provided therein; means for 20 propelling balls one at a time onto the upper portion of said inclined playing board so that they may gravitate thereover and enter into said exit opening; an inclined runway arranged below said inclined playing board in communication 25 with said ball exit opening for conducting spent balls back to a point adjacent to but below said propelling means, said runway having a ball exit opening or pocket provided therein; a score indicating device in said cabinet including an indicator member having spaced indicia thereon 30 movable at different times into registration with said sight opening; means actuated by balls entering said pocket from the said runway to move said indicator at different times in opposite directions and thereby move said indicia selectively 35 into registration with said sight opening arranged in said cabinet; and a ball-releasing member below said pocket for temporarily holding balls therein and said second-named means in effective position. 40
7. In a game apparatus, the combination of: a cabinet having a sight opening formed therein and including an inclined playing board having a ball exit opening provided therein; means for 45 propelling balls one at a time onto the upper portion of said inclined playing board so that they may gravitate thereover and enter into said exit opening; an inclined runway arranged below said inclined playing board in communication 50 with said ball exit opening for conducting spent balls back to a point adjacent to, but below, said propelling means; said runway having a ball exit opening or pocket provided therein; means dividing said runway into branches; a score indicating device in said cabinet including a segmental indicator dial having spaced indicia thereon 55 selectively movable into registration with said sight opening and having a relatively blank space thereon between said indicia; means normally urging said indicator dial into a position to dispose 60 said relatively blank space in registration with said sight opening; and means actuated by balls entering said pocket from the said runway to move said indicator at different times in opposite directions and said indicia selectively into 65 registration with said sight openings. 70
8. In a game apparatus, the combination of: a cabinet having a bank of sight openings provided 75 therein arranged in acrostic rows and said cabinet including an inclined playing board provided with ball exit or scoring openings; means for propelling balls one at a time onto the upper portion of said inclined playing board so that they may gravitate thereover and enter into said ball exit or scoring openings; inclined runways arranged in said cabinet below said inclined playing board for conducting spent balls to a point adjacent to, but below, said propelling means and each of said runways having communication with a preselected number of said ball exit or scoring 75
- arranged in said cabinet below said inclined playing board for conducting spent balls to a point adjacent to, but below, said propelling means and each of said runways having communication with a preselected number of said ball exit or scoring openings; a score indicating device arranged in said cabinet below each of said sight openings and each of said score-indicating devices including an indicator having spaced score-indicating indicia thereon and each of said indicators having a relatively blank space thereon in registration with the corresponding one of said sight openings; each of said runways having a ball exit opening or pocket formed therein in the lower portion thereof; and each of said score-indicating devices including means actuated by balls traveling from the corresponding one of said runways into the said pocket formed therein to move the corresponding one of said indicators, at different times, against the action of the said urging means, into a position to dispose the said indicia thereon selectively in registration with the corresponding one of said sight openings. 10
9. In a game apparatus, the combination of: a cabinet having a bank of sight openings provided 25 therein arranged in acrostic rows and said cabinet including an inclined playing board provided with ball exit or scoring opening; means for propelling balls one at a time onto the upper portion of said inclined playing board so that they may gravitate thereover and enter into said ball exit or scoring openings; inclined runways arranged in said cabinet below said inclined playing board for conducting spent balls to a point adjacent to, but below, said propelling means and each of said runways having communication with a preselected number of said ball exit or scoring openings; a score indicating device arranged in said cabinet below each of said sight openings and each of said score-indicating devices including an indicator having spaced score-indicating indicia thereon and each of said indicators having a relatively blank space thereon between said indicia; means normally urging each of said indicators into position to dispose 30 the said relatively blank space thereon in registration with the corresponding one of said sight openings; each of said runways having a ball exit opening or pocket formed therein in the lower portion thereof; each of said runways including branches and said branches having communication independently relative to each other with a corresponding one of said pockets; and each of said score-indicating devices including means actuated by balls traveling from the said 35 branches of the corresponding one of said runways into the said pocket formed therein to move said indicators, at different times, against the action of the said urging means, into a position to dispose the said indicia thereon selectively in 40 registration with said sight openings. 45
10. In a game apparatus, the combination of: a cabinet having a bank of sight openings provided 50 therein arranged in acrostic rows and said cabinet including an inclined playing board provided with ball exit or scoring openings; means for propelling balls one at a time onto the upper portion of said inclined playing board so that they may gravitate thereover and enter into said ball exit or scoring openings; inclined runways arranged in said cabinet below said inclined playing board for conducting spent balls to a point adjacent to, but below, said propelling means and each of said runways having communication with a preselected number of said ball exit or scoring 55

openings; a score indicating device arranged in said cabinet below each of said sight openings and each of said score-indicating devices including an indicator having spaced score-indicating 5 indicia thereon; each of said indicators having a relatively blank space thereon between said indicia; means normally urging each of said indicators into position to dispose the said relatively blank space thereon in registration 10 with the corresponding one of said sight openings; each of said runways having a ball exit opening or pocket formed therein in the lower portion thereof; each of said runways including branches and said branches having communication independently relative to each other 15 with the corresponding one of said pockets; and each of said score-indicating devices including means, actuated by balls traveling from the said branches of the corresponding one of said 20 runways into the said pocket formed therein, to move said indicators, at different times, and in opposite directions, against the action of the said urging means, into a position to dispose the said indicia thereon selectively in registration with 25 said sight openings.

11. A game apparatus, comprising: a cabinet having a sight opening therein and including a member providing a playing surface having a ball exit opening therein; means for propelling 30 balls over said playing surface so that they may enter into said exit opening; a ball return runway below said playing surface having communication 35 with said exit opening; a score indicator pivotally mounted in said cabinet below said sight opening; and means including a member arranged in said runway and operable by a ball traveling therealong for pivoting said score indicator, at different times, in opposite directions, into registration with said sight opening.

12. A game apparatus, comprising: a cabinet having a sight opening therein and including a member providing a playing surface having a ball exit opening therein; means for propelling balls 40 over said playing surface so that they may enter into said exit opening; a ball return runway below said playing surface having communication with said exit opening; a score indicator 45 movably mounted in said cabinet below said sight opening; and means including a member arranged in said runway and operable by a ball traveling therealong for moving said score indicator, at different times, in opposite directions, into registration with said sight opening.

13. A game apparatus, comprising: a cabinet 55 including a member providing a playing surface having a ball exit opening therein; means for propelling balls over said playing surface so that they may enter into said exit opening; a ball return runway below said playing surface having communication with said exit opening; a score 60 indicator pivotally mounted in said cabinet; and means including a member arranged in said runway and operable by a ball traveling therealong for pivoting said score indicator, at different times, in opposite directions.

14. A game apparatus, comprising: a cabinet including a member providing a playing surface having a ball exit opening therein; a ball return runway below said playing surface having communication with said exit opening; a score 65 indicator movably mounted in said cabinet; and

means including a member arranged in said runway and operable by a ball traveling therealong for moving said score indicator, at different times, in opposite directions.

15. A game apparatus, comprising: a cabinet having a sight opening therein and including a member providing a playing surface having a ball exit opening therein; means for propelling balls over said playing surface so that they may enter into said exit opening; a ball return runway in said cabinet below said playing surface and having communication with said ball exit opening; said runway having communicating branches; a score indicator pivotally mounted in said cabinet below said sight opening; and means including a member having a portion arranged in each of the said branches of said runway and engageable by a ball traveling therealong for pivoting said score indicator, at different times, in opposite directions, into registration with said sight 20 opening.

16. A game apparatus, comprising: a cabinet having a sight opening therein and including a member providing a playing surface having a ball exit opening therein; means for propelling balls 25 over said playing surface so that they may enter into said exit opening; a ball return runway in said cabinet below said playing surface and having communication with said ball exit opening; said runway having communicating branches; a score indicator movably mounted in said cabinet below said sight opening; and means including a member having a portion arranged in each of the said branches of said runway and engageable by a ball traveling therealong for moving 30 said score indicator, at different times, in opposite directions, into registration with said sight opening.

17. A game apparatus, comprising: a cabinet having a sight opening therein and including a member providing a playing surface having a ball exit opening therein; means for propelling balls 35 over said playing surface so that they may enter into said exit opening; a ball return runway in said cabinet below said playing surface and having communication with said ball exit opening; said runway having communicating branches; a score indicator pivotally mounted in said cabinet below said sight opening; and means including an element arranged in each of the said branches 40 of said runway and engageable by a ball traveling therealong for pivoting said score indicator, at different times, in opposite directions, into registration with said sight opening.

18. A game apparatus, comprising: a cabinet 55 having a sight opening therein and including a member providing a playing surface having a ball exit opening therein; means for propelling balls over said playing surface so that they may enter into said exit opening; a ball return runway in 60 said cabinet below said playing surface and having communication with said ball exit opening; said runway having communicating branches; a score indicator movably mounted in said cabinet below said sight opening; and means including an element arranged in each of the said branches 65 of said runway and engageable by a ball traveling therealong for moving said score indicator, at different times, in opposite directions, into registration with said sight opening.

JOHN B. FIRESTONE.
